UNITED STATES PATENT OFFICE.

JONATHAN L. BEARDEN, OF SPRINGFIELD, MISSOURI.

KITCHEN-CABINET.

SPECIFICATION forming part of Letters Patent No. 361,667, dated April 26, 1887.

Application filed August 25, 1885. Serial No. 175,274. (No model.)

To all whom it may concern:

Be it known that I, JONATHAN L. BEARDEN, a citizen of the United States, residing at Springfield, in the county of Greene and State 5 of Missouri, have invented certain new and useful Improvements in the Combination of a Flour-Chest and Mold-Board; and I do hereby declare the following to be a full, clear, and exact description of the invention, such as will enable others skilled in the art 10 to which it appertains to make and use the same.

My invention relates to improvements in the combination of a mold-board and flour-chest, the object of which is to provide a cheap, simple, durable, and convenient device for holding flour, meal, and other culinary articles, and at the same time one that will serve as a shelf or mold-board when desired. These objects I attain by means of the device illustrated in the accompanying drawings, forming a part of this specification, in which—

Figure 1 is a perspective view of the device 25 open ready for use. Fig. 2 is a similar view of the device closed.

A is a chest or box having drawers in its lower part. Said drawers are provided with suitable flanges, so as to fit close against the 30 chest, and thus make a tight joint. The drawer a is preferably made of sufficient capacity to hold one hundred pounds of flour. Said drawer is provided with a suitable handle or knob, a' , for drawing it out when it is 35 desired to clean, empty, or fill the drawer.

a' a^2 are small drawers, and are preferably made so as to hold about fifty pounds of flour or meal each, and are each provided with a handle or knob, a' a^2 , so as to draw them out 40 when desired.

B is a mold-board, which serves as a door when turned up against the upper part of the chest or box. Said mold-board is provided with projecting end pieces, b b , to hold 45 the flour upon the same. The board B is also provided with suitable hinges, b' , for hinging it to the cross-piece a^3 .

E E are suitable supports pivoted to the ends and near the outer edges of the mold-board, the lower part of the same being pivoted to the ends of arms F, said arms being pivoted near the middle and lower ends of the chest.

C is a partition dividing the lower and upper part of the chest, the front part of which 55 is hinged so as to swing back and permit the contents of the drawers a and a' to be taken out above the board.

D is a partition placed at any desired distance above the partition C, leaving a space 60 which may be used for any desired purpose, and is provided with the cross-partitions d , d' , d^2 , d^3 , d^4 , and d^5 , so as to form partitions for the drawers M, G, H, I, J, K, and L. Said drawers are for the purpose of holding spices, 65 sugars, and the like. Each drawer is provided with a suitable handle or knob. These drawers are closed inside of the chest by the mold-board B, so as to prevent insects from getting at their contents.

The chest A is provided with a suitable top, ends, sides, and bottom, so as to make it insect-tight when closed. The front side is preferably made beveling upward and backward from the top of the cross-piece a^3 to the 70 point where the top of the door or mold-board strikes the side of the chest. The partition N is to divide the lower part of the chest into two parts. Said partition preferably extends from the bottom of the chest to the partition 75 C, and from the front to the rear of the chest, so as to prevent the contents of the different parts mixing.

O is a partition running parallel with the bottom of the chest and extends from the end 80 P to the partition N, and serves as a support 85 to the drawer a' .

I am aware of the construction shown in Letters Patent No. 327,801, kitchen-cabinet, and make no claim thereto.

Having thus described my invention, what I claim as new, and desire to secure by Letters Patent, is—

The combination, with a flour-chest, A, and swinging mold-board B, provided with end 90 pieces, b b , of supports E E , hinged to the mold-board, and arms F F , pivoted to the chest and to the supports, substantially as and for the purpose set forth.

In testimony whereof I affix my signature in 95 presence of two witnesses.

JONATHAN L. BEARDEN.
